233,963

T-SLING CHAIR

Gerry D. Welton, 910 E. Tripp, Peoria, Ill. 61603
Filed May 1, 1973, Ser. No. 356,104

Term of patent 14 years

Int. Cl. D6—01
U.S. Cl. D6—55

FIG. 1 is a front perspective view of a T-sling chair embodying my new design.

FIG. 2 is a rear perspective view of the T-sling chair shown in FIG. 1.

FIG. 3 is a side elevation of the T-sling chair shown in FIG. 1 and FIG. 2.

I claim:

The ornamental design for T-sling chair, as shown.
